UNITED STATES PATENT OFFICE.

CLARKE S. DRAKE, OF MILWAUKEE, WISCONSIN.

ENGINE-COOLING INDICATOR.

Application filed September 3, 1920. Serial No. 407,960.

To all whom it may concern:

Be it known that I, CLARKE S. DRAKE, a citizen of the United States, and resident of Milwaukee, county of Milwaukee, and State of Wisconsin, have invented new and useful Improvements in Engine-Cooling Indicators, of which the following is a description, reference being had to the accompanying drawings, which are a part of this specification.

The invention relates to a device for indicating the condition of the cooling fluid of an internal combustion or other engine and by which the temperature, specific gravity and circulation of said fluid may be observed.

One of the objects of the invention is to provide an indicator for the cooling fluid system to admit of operation at a distance from the engine or motor so that it can be mounted on the dash or instrument board of automobiles, in the pilot house or cabin of a boat, in the engine room of an industrial plant or in the cockpit of an aeroplane.

A further object of the invention is to provide certain improvements in the connection of the device with the cooling fluid circulating system over that shown in my prior Patent, No. 1,202,977, granted to me October 31, 1916.

A further object of the invention is to provide an indicating device for the cooling system in which the specific gravity of the cooling fluid at any temperature may be readily determined so that the operator will know whether the fluid in the cooling system in cold weather has the proper amount of freezing preventive in it.

The invention further consists in the several features hereinafter set forth and more particularly defined by claims at the conclusion hereof.

In the drawings: Fig. 1 is an elevation view of an engine and its cooling system showing the indicator connected therewith; Fig. 2 is a front view of the indicator; Fig. 3 is a side view of the indicator; Fig. 4 is a front view of the indicator, parts being broken away and parts being shown in section; Fig. 5 is a section taken on the line 5-5 of Fig. 4.

In the drawings the numeral 6 designates the casing of the indicating device having a circular chamber 7 provided with a recessed flange 8 in which a glass front 9 is

mounted between packing rings 10 and clamped to the flange 8 by a ring 11 having threaded connection with said flange. The casing 6 is provided with a removable top 12 having an opening 13 covered with a glass plate 14 and an incandescent lamp 15 is carried by the top and enclosed by a cover 16, the light from the lamp passing through the plate 14 serving to illuminate the interior of the casing.

A fountain tube is mounted in the base of the casing and extends into the chamber 7. This tube is connected by a pipe 18 to the cooling system of the engine and in Fig. 1 is shown connected to the outlet pipe 19 from the water jacket of the engine 20, a cut off valve 21 being provided in the pipe 18.

A padded cup 22 is mounted in the base and receives the lower end of a hydrometer or other instrument 23 for indicating specific gravity, the stem of which passes loosely through a ring bracket 24 in the chamber 7.

A thermometer 25 is mounted in the casing, its lower end resting on a piece of soft material 26 with its stem passing through a collar 27 removably mounted in a ledge 28 in the casing. A plate 29 is also mounted in the casing having temperature graduations 30. The lower end of the thermometer being disposed in the bottom of the casing some of the water in circulating through the casing comes in contact with the thermometer bulb.

A pipe 31 connects the interior of the casing with the cooling system and preferably with the suction end of the system as to a pipe 32 where a pump or other circulating device 33 or suction producing means is employed to draw the cooling fluid from the radiator 34 and force it into the water jackets of the engine from which it passes through pipe 19 back to the radiator. The connection of the pipe 31 with the suction side of the circulating device is important and of great advantage as the suction pressure created by the device always insures a portion of the water from the pipe 19 being drawn through the pipe 18 and tube 17 into the casing and thence through the pipe 31 to the suction end of the cooling system.

The water on being drawn through the tube 17 issues from its upper end in the form of a fountain and as the device is attached to the instrument board, when used on a motor driven vehicle, the action of the cooling

fluid may be readily observed. Furthermore, the connection of the pipe 18 with the lower end of the outlet pipe 19 or to the upper portion of the water jacket of the engine insures the hottest water circulating through the device so that the thermometer in the casing will indicate substantially the temperature of the cooling fluid.

In the taking of a specific gravity reading it is desirable to hold a certain amount of the cooling fluid in the casing 6 so that the reading may be taken at a predetermined temperature. For this purpose I provide a branch pipe connection 36 extending from the upper part of the casing 6 to the pipe 31 and having valve housing 37 between its ends provided with a push button valve 38 controlling an atmospheric vent 39. The pipe 36 connects with a valve casing 40 of the pipe 31. A plug valve 41 is mounted in the casing 40 and has an opening 42 therein to allow free passage of fluid through the pipe 31, as shown in Fig. 4, or to establish communication between the pipe 36 and the pipe 31, a portion of the valve seat being cut out to form a passage 43 for this purpose.

With the valve 41 in the position shown in Fig. 4 the suction action of the circulating device will produce a flow of the cooling liquid through the indicator, and its action may be observed by the passage of the cooling fluid from the fountain tube 17, as previously described. From this action the operator may observe whether the fluid in the cooling system is present in the proper quantity and is circulating. He may also at any time observe the indication of the thermometer to see whether the engine is overheating or under heating.

When the two-way valve 41 is turned so as to establish communication between pipes 36 and 31 the suction is diverted from the lower to the upper end of the casing 6 and in this way the casing may be filled with cooling fluid and then the valve 41 may be turned to closed position so that a portion of the circulating fluid will be trapped in the device. This trapped fluid may then be allowed to cool down until it reaches such a temperature as to give a direct reading of the scale on the instrument 23. When it is desired to exhaust the fluid from the device it is only necessary to open valve 41 and press in the valve 38, thereby opening the vent 39 to the atmosphere and by admitting air the suction on the pipe entering the device is lessened and the fluid will run out faster than it can enter the device, or if the valve 21 is closed and the vent opened the fluid in the device will be sucked out rapidly. This arrangement enables the operator to vary at will the amount of fluid taken into or drawn out of the device so that the fluid may be maintained in the de-

vice at any desired height in order that specific gravity indications at a predetermined temperature may be readily taken without having to make allowances for variation in temperature in computing the correct reading of specific gravity.

If the specific gravity of the cooling fluid is known and the ingredients of the same are also known, it is possible to determine the freezing or boiling point of the fluid or any other data which may be determined from the specific gravity. In this way the operator may know whether he has the proper proportion of freezing preventive in the cooling fluid in times of cold weather.

From the foregoing description it will be noted that the device enables the operator to determine whether the cooling fluid is circulating properly, as a stream of water will flow through the device when the engine is properly furnished with cooling water. It is obvious that any derangement in the cooling system resulting in loss of cooling fluid either by steaming out or leakage would cause the cooling fluid to cease flowing through the device as soon as the level of the cooling fluid contained in the cooling system falls below the point of attachment to said cooling system of pipe 18.

The device enables the operator to determine the temperature of the cooling fluid and by auxiliary devices the temperature of the cooling fluid within the water jackets may be kept at that point at which the motor operates at greatest efficiency.

When it is necessary to use freezing preventives in the cooling fluid it is desirable to know the quantity of preventive in the cooling fluid and its freezing point. This information may be readily obtained by using the instrument to indicate the specific gravity of the cooling fluid.

I desire it to be understood that this invention is not limited to any specific form or arrangement of parts except in so far as such limitations are specified in the claims.

What I claim as my invention is:

1. In an indicator device, the combination, of a casing in communication with the cooling system of an engine and having a transparent wall, a thermometer in said casing to indicate the temperature of the fluid in said system; an instrument in said casing to indicate the specific gravity of said cooling fluid, and means in said casing providing a visible indication of the flow of the cooling fluid.

2. The combination, with the cooling system of an internal combustion engine including a water jacket and a circulating device, of a casing having a transparent wall and a means providing a visible indication of the flow of the cooling liquid, means establishing communication between said casing and the suction side of said circulating device,

and means establishing communication between said casing and the cooling liquid leaving the water jacket of the engine.

3. The combination, with the cooling system of an internal combustion engine including a circulating device, of a casing at a distance from the engine and in a position to be readily observed by the operator, an outlet connection between this casing and the suction side of said device, and an inlet connection between said casing and the cooling liquid leaving the water jacket of the engine, said inlet connection including a fountain tube and said casing having a window therein adjacent said tube.

4. In an indicator device of the character described, the combination with a casing in communication with the cooling system of an engine, of a thermometer and an instrument for indicating specific gravity disposed in said casing, and means for trapping a portion of the fluid from the cooling system in said casing to obtain a specific gravity indication at a predetermined temperature.

5. In an indicator device of the character described, the combination, with a cooling system of the engine, of a casing in communication with said system and having a transparent wall, means in said casing providing a visible indication of the flow of the cooling fluid, a thermometer and an instrument for indicating specific gravity disposed in said casing, and means for trapping a portion of the fluid from the cooling system in said casing to obtain a specific gravity indication at a predetermined temperature.

6. In an indicator device of the character described, the combination of a casing having communication with the cooling system

of an engine, outlet connections from the lower and upper ends of said casing, a valve controlling the passage through either of said connections, and a valve controlled vent in the outlet connection leading to the upper end of the casing.

7. In a cooling system for an internal combustion engine having a water jacket, a means for indicating the presence of a normal supply of water in said system, comprising a chamber having a transparent wall, means for producing suction in said chamber, and means for supplying an indicating stream of water from said water jacket to said chamber under the influence of the suction.

8. In a cooling system for an internal combustion engine having a water jacket, the combination of a means for indicating the presence of a normal supply of water in said system comprising a chamber having a transparent wall, means for producing suction in said chamber, means for supplying an indicating stream of water from said water jacket to said chamber under the influence of suction, and means for indicating the temperature of the water in said chamber.

9. The combination with the cooling system including the jacket space of the engine, a chamber, means for creating suction in said chamber, means for supplying cooling water leaving the jacket space of the engine to said chamber responsive to suction, said chamber discharging into the cooling system, and means for indicating the temperature of the water in said chamber.

In testimony whereof, I affix my signature.

CLARKE S. DRAKE.
